Primary Examiner — Patricia Palasik

(74) Attorney, Agent, or Firm — Jacobson Holman,
PLLC.(57) **CLAIM**

We claim an ornamental design for a sanding machine, as shown and described.

DESCRIPTION

FIG. 1 is a front perspective view of the sanding machine embodying our design;

FIG. 2 is a top plan view of FIG. 1;

FIG. 3 is a bottom view of FIG. 1;

FIG. 4 is a right side elevational view of FIG. 1;

FIG. 5 is a left side elevational view of FIG. 1;

FIG. 6 is a front elevational view of FIG. 1; and,

FIG. 7 is a rear elevational view of FIG. 1.
